UNITED STATES PATENT OFFICE.

ADOLF VON REICHELT, OF PURKERSDORF, AUSTRIA-HUNGARY, ASSIGNOR TO THE FIRM OF HIRSCH & FÜRST, OF VIENNA, AUSTRIA-HUNGARY.

APPARATUS FOR RAISING SUNKEN OBJECTS.

1,120,743.

Specification of Letters Patent.

Patented Dec. 15, 1914.

Application filed April 30, 1914. Serial No. 835,381.

To all whom it may concern:

Be it known that I, ADOLF VON REICHELT, subject of the Emperor of Austria-Hungary, residing at Purkersdorf, in the Empire of 5 Austria-Hungary, have invented certain new and useful Improvements in Apparatus for Raising Sunken Objects, of which the following is a specification.

My invention relates to apparatus for 10 raising sunken objects and more particularly to that kind which comprises a buoy provided with a grab device and in which the buoyancy is obtained by means of compressed air or gas.

15 In accordance with my invention the grab gear suspended from the buoy is placed in communication with the discharge valve of the pressure medium reservoir by means of a flexible, stretched member which is slack 20 when the grab arms make contact and permits of the opening of the discharge valve, while at the same time the closing of the contracting grab arms is effected by the automatic release of hooks previously holding 25 these arms open.

By means of links auxiliary buoys are connected with the main buoy and are adapted to be released from their inoperative deep position by a traction member 30 adapted to be operated from the surface of the water. The auxiliary buoys can be charged with the pressure medium by simultaneous opening of cocks, so that if the grab arms should become buried in the 35 ground additional buoyancy can be brought to bear upon them while they are deprived of a support which acts upon them in their closed position and at the same time owing to the sudden relief the main buoy is caused 40 to ascend and the grab arms are caused to separate.

The invention is illustrated by way of example in the accompanying drawing, in which:—

45 Figure 1 shows the apparatus in section: the left half of the figure represents one of the grab arms (shown broken off) in its closed position while the right half shows the other arm in its open position. Fig. 2 50 is a plan of the apparatus. Fig. 3 is a vertical axial section of the discharge valve of the air reservoir. Fig. 4 is a similar view showing the regulating valve for the air reservoir. Fig. 5 represents an air-heating 55 furnace in vertical axial section. Fig. 6

shows in vertical section the air discharge valve of the buoy; the left half showing the valve closed and the right half open. Fig. 7 is a section along A—A in Fig. 6, illustrating an arrangement of levers acting 60 upon the valve. In the upper half of this figure the position of these levers is that occupied when the valve is closed, and in the lower half when it is open.

The cylindrical body of the main buoy 1 65 is provided with conical ends, which ends are strengthened by cast collars 2 and 3, respectively, the latter acting also as supports for a concentrically arranged air reservoir 4. By means of a charging valve 5 70 the air reservoir is charged in a well known manner with high tension compressed air. Upon the upper collar 3 a hood 7 provided with an air cock 6 is fitted in an airtight manner. In order to prevent the buoy from 75 rotating while it is being sunk, longitudinal fins 8 are provided upon the body 1 of the buoy; these fins insure the grab arms making contact in a given position. Upon the air reservoir 4 in addition to the charging 80 valve 5 a discharge valve 9, a regulating valve 10 and an air heating furnace 11 are arranged.

The discharge valve 9 (Fig. 3) can be caused to open inwardly by the pressure of 85 a spring 12 when the tension of a cable 16 which preponderates over the action of the spring, ceases; this cable is fixed with one end to the longer arm of a bell-crank lever 14 acting as a pawl and pivoted to a lug of 90 the valve casing 13 and with its other end to the supports 15 of a grab gear (Fig. 1). The compressed air can then flow through a pipe 9' from the air reservoir 4.

Fig. 3 shows that when the cable 16 again 95 becomes taut the valve is not closed thereby; this closing can only be effected by hand by means of a pawl 17 which bears against the shorter arm of the bell crank lever 14 and is adapted to compress the spring 12; the 100 valve is then again pressed against its seat by means of a spring 12'.

The regulating valve 10 (Fig. 4) is actuated by means of a float 18 (Fig. 1) provided in the interior of the buoy 1 and 105 mounted on the upwardly extending arm of a double lever 19; this lever is pivoted to a supporting arm 20 which is fixed to a tube 21 centrally arranged on the upper deck of the buoy. This tube serves to insure the 110

floating capacity of the buoy even when the hood is removed as by this means a certain volume of air is always retained in the buoy. To the valve hood 22 (Fig. 4) a one-armed lever 23 is pivoted, its end being connected by means of a cable 24 with the horizontal arm of the double lever 19 carrying the float. A nose on the lever 23 bears against the stem of the valve; if the float rises in the buoy, 5 by means of the cable 24 and of the lever 23, the valve stem is depressed and the valve being opened thereby the compressed air can escape from the air reservoir 4, through the tube 10'. When the water level in the 10 buoy descends, the cable 24 slackens and the valve is again closed by the gas pressure and the action of springs 25 and 26. The compressed air escaping through the pipes 9' and 10" of the discharge and regulating 15 valves is conducted to the air heating furnace 11 (Fig. 5). This furnace is of known construction and serves to heat the air by means of benzin flames from a plurality of heating lamps 27 arranged in a circle provided for the purpose of preventing the 20 formation of ice in the buoy.

An air discharge valve 28 is mounted on the upper end of the buoy 1 (Figs. 6 and 7), and by the buoyancy of a float 29 mounted 25 on the lower end of the valve stem 30 (Fig. 1) this valve can be closed when the water level in the buoy has reached a given height. On the upper end of the valve stem, is a 30 guide cylinder 32 provided in its circumference with an annular groove 31; this cylinder is guided in the spring bush 33. The latter is supported by a spring 34 and comprises two sector-shaped recesses 35 (Fig. 7), through which the air is able to escape 35 from the interior of the buoy when the valve is open. As shown in the lower half of Fig. 7, when the valve is open, two pawl levers 37 mounted on pivots 36 are pressed by springs 38 against the guide cylinder 32 above the 40 groove 31; at the same time the ends of the pawl levers engage an annular groove 39 in the valve casing 40 and thereby prevent the spring bush 33 which is subjected to the action of the spring 34 from rising. Now if 45 the valve stem and the guide cylinders rise under the influence of the float 29, the pawl levers descend as shown in the upper half of Fig. 7, under the influence of the springs 38 and engage the annular groove in the guide 50 cylinder the support for the spring bush against the casing ceasing at the same time and the bush now being pressed upward by the spring 34. One can reopen the valve only 55 by hand by simultaneously separating and depressing hand claws arranged in bores 41 to which the springs 38 are also fixed; by 60 this means the pawl levers are caused to assume the position indicated above.

The longitudinal fins 8 (Figs. 1 and 2) 65 carry at their lower edge pivots 42 and at

their upper edge pivots 43 of which the former serve for the suspension of the grab device by means of chains or the like and the latter for the provision of crane chains which are used in lowering and raising the 70 buoy. The grab gear is suspended from the pins 42 by means of chains 44; this gear consists of two supports 15 connected one with the other by four bolts 45, 46. The two outer bolts 45 to which the chains 44 are 75 fixed carry the grab arms 48 by means of two pairs of hooks 47 the said arms being mounted in a trough 50 by means of bolts 49. On their inner ends, the grab arms carry rollers 52 rotatable about pins 51. Upon the 80 bolts 46, hooks 53 are rotatably mounted, their jaws embracing the rollers 52 against which they are pressed by means of tension springs 54.

The pins 42, 43 mounted in the two pairs 85 of fins 8 serve as pivots for pairs of links 55 which carry auxiliary buoys 58 by means of the pivots 56, 57; these auxiliary buoys are closed at the top by means of cocks 59, while at the bottom they are open. They communicate through pipes 60 with the interior of the main buoy 1. The pipes 60 are rotatably mounted in stuffing boxes 61 on the auxiliary buoys and open into cock casings 62 on the body of the main buoy 1. On the lower 90 pivot pins 56 of each auxiliary buoy a cable 63 is fixed; these cables pass over guide rollers 64 and are attached to the upper arm of the corresponding hook 53. The plug of the cock 62 can be rotated by means of a lever 65 95 which is pivotally connected with a bell crank lever 67 by means of a link 66; by means of a claw 68, this lever 67 embraces a connecting pin 69 of the upper pair of links 55 and to its upper end, is attached with a 100 cable 70 by means of which the buoy links can be unlocked and the cocks 62 opened.

The operation of the device is as follows: When the hood 7 is removed and the air discharge valve 28 closed the air reservoir 4 of 110 the buoy which is maintained above water is filled by means of a compressor with high pressure air by means of the charging valve 5; the discharge valve 9 and regulating valve 10 are closed. The burners of the air heating furnace 11 are lighted; the hood 7 is screwed on to form an airtight joint and the valve 28 is opened by hand. Owing to the discharge of the air, the buoyancy is lost and the buoy descends while the water level in the buoy rises until the float 29 closes and locks the valve 28. The lower the buoy sinks, the more the air contained therein is compressed so that owing to the constantly diminishing buoyancy, the velocity of the 115 descent would constantly increase; this velocity should not however exceed a given amount as otherwise on striking against the ground, the apparatus might be damaged. Increase in the velocity of descent beyond a 120 125 130

given limit is prevented by the regulating valve 10 actuated by the float 18 and which allows the air to flow out of the reservoir 4, the float maintains the water level in the 5 buoy at the same height as it opens or closes the valve when the water level in the buoy tends to rise or fall.

When the buoy enters the water the grab arms are suspended with the hooks 47 on the pivots 45 of the grab gear and are supported in their position by the upper jaws of the hooks 53. On encountering the ground, in the first place the grab arms 48 and the trough 50 come to rest while the 10 grab gear 15 and the buoy continue to descend for some time under the influence of inertia. By this means the hooks 47 are reversed (see left hand half of Fig. 1), while the engagement of the rollers 52 in the 15 mouths of the hooks is insured by the spring 54. At the same time the cable 16 is slackened, the spring 12 opens the discharge valve 9 of the air reservoir 4 and air flows through the air heating furnace 11 into the 20 buoy and expels the water contained therein through the supporting collar.

As the quantity of air constantly maintained in the buoy during its descent is calculated in such a manner that although its 25 buoyancy is smaller than the total weight of the buoy plus the grab it is greater than that of the buoy alone. While therefore after reaching the bottom, the buoy continues to descend somewhat, it immediately 30 afterward rises again, whereby the suspension chains 44 are stretched. The grab arms are supported by their rollers 52 on the lower jaws of the hooks 53 which jaws must be given such a curvature that the rollers 35 are securely held in position.

In order to avoid losing the entire apparatus in case it should become fast in the ground, prior to the sinking of the lifting buoy, the air is discharged from the auxiliary buoys 58 by opening the cocks 59 whereupon the cocks are again closed. By 40 this means the auxiliary buoys can be locked in their deep position, that is to say, the cocks 62 remain closed. If the grabs of the buoy 45 have become fast in the ground by exerting a pull on the cable 70, the locking means of the auxiliary buoys is released and the cocks 62 are opened, so that the air contained in the body of the main buoy after having 45 already expelled the water from the latter, flows into the auxiliary buoys. The buoyancy thus produced causes the auxiliary buoys to rise, the lower link pin assumes the 50 position 56 so that the cables 63 are drawn over the guide rollers 64 and the hooks 53 are opened releasing the rollers 52 and the grab arms 48. The buoy ascends owing to the sudden relief and by means of the chains 55 which have hitherto hung down slack 55 raises the grab arms, whereby their claws 72

are released and the main buoy is now able to rise to the surface of the water. The cable 70 can be rendered taut by means of a small windlass mounted in a float-buoy anchored to the cable 73.

70

I claim—

1. Apparatus for raising sunken objects comprising a buoy, a closed reservoir therein, adapted to be charged with a pressure medium, a grab gear loosely suspended from said buoy, a discharge valve on said reservoir normally closed, a member controlling said discharge valve and a normally taut flexible connection between said controlling member and said grab gear, adapted to permit the opening of the discharge valve when relaxed.

75

2. Apparatus for raising sunken objects comprising a buoy, a closed reservoir therein, adapted to be charged with a pressure medium, a grab gear loosely suspended from said buoy, a discharge valve on said reservoir normally closed, a spring tending to open said discharge valve, a pawl co-acting with said spring, a pawl lever adapted to lock said pawl in position, and a normally taut flexible connection between said pawl lever and said grab gear adapted to release said pawl lever when relaxed, thereby permitting the said spring to open the said 90 discharge valve.

85

3. Apparatus for raising sunken objects comprising a buoy, a closed reservoir therein adapted to be charged with a pressure medium, a grab gear loosely suspended from said buoy, a regulating valve on said reservoir normally closed, a lever controlling said regulating valve, a float in said buoy, a pivoted bent lever carrying said float, a flexible connection between said bent lever and said 100 valve controlling lever to cause the opening of said regulating valve as the said float rises, and means for automatically closing said regulating valve upon the sinking of said float.

105

4. Apparatus for raising sunken objects comprising a buoy, a closed reservoir therein adapted to be charged with a pressure medium, a grab gear loosely suspended from said buoy, a regulating valve on said reservoir normally closed, a lever controlling said regulating valve, a float in said buoy, a pivoted bent lever carrying said float, a flexible connection between said bent lever and said valve controlling lever to cause the 110 opening of said regulating valve as the said float rises, and means for automatically closing said regulating valve upon the sinking of said float, and a discharge valve on said reservoir controlled by the position of 120 said grab gear.

115

5. Apparatus for raising sunken objects comprising a buoy, a closed reservoir therein adapted to be charged with a pressure medium, a grab gear loosely suspended from 130

said buoy, a regulating valve on said reservoir normally closed, a lever controlling said regulating valve, a float in said buoy, a pivoted bent lever carrying said float, a flexible connection between said bent lever and said valve controlling lever to cause the opening of said regulating valve as the said float rises, means for automatically closing said regulating valve upon the sinking of said float, a discharge valve on said reservoir controlled by the position of said grab gear, an air heating furnace mounted on said reservoir and connections between said furnace and said two valves causing the air to pass through said furnace.

6. Apparatus for raising sunken objects comprising a buoy, a closed reservoir therein adapted to be charged with a pressure medium, a grab gear loosely suspended from said buoy, a regulating valve on said reservoir normally closed, a lever controlling said regulating valve, a float in said buoy, a pivoted bent lever carrying said float, a flexible connection between said bent lever and said valve controlling lever to cause the opening of said regulating valve as the said float rises, means for automatically closing said regulating valve upon the sinking of said float, and a short tube concentrically surrounding said reservoir down to a certain depth below the level of the water in said buoy to prevent the entire escape of air.

7. Apparatus for raising sunken objects comprising a buoy, a closed reservoir therein adapted to be charged with a pressure medium, a grab gear loosely suspended from said buoy, a discharge valve on said reservoir, a flexible connection between said discharge valve and said grab gear, a regulating valve on said reservoir, a float in said buoy and connections between said float and said regulating valve, a discharge valve on said buoy, means for opening the last mentioned discharge valve, and a float in said buoy connected with the valve stem of said last mentioned discharge valve and adapted to close the same upon a predetermined rise of said float.

8. Apparatus for raising sunken objects comprising a buoy, a closed reservoir therein adapted to be charged with a pressure medium, a grab gear loosely suspended from said buoy, a discharge valve on said reservoir, a flexible connection between said discharge valve and said grab gear, a regulating valve on said reservoir, a float in said buoy and connections between said float and said regulating valve, a discharge valve on said buoy, means for opening the last mentioned discharge valve, a float in said buoy connected with the valve stem of said last mentioned discharge valve and adapted to close the same upon a predetermined rise of said float, a guide cylinder mounted on said valve stem and provided with a groove and

spring controlled pawl levers engaging a groove in the valve casing while the valve is open and adapted to enter the groove in said guide cylinder when the valve is closed, thereby locking the valve in closed position. 70

9. Apparatus for raising sunken objects comprising a buoy, a closed reservoir therein adapted to be charged with a pressure medium, a support loosely suspended from said buoy, hooks pivoted to said support and provided with jaws, grab arms held by said jaws, hooks pivoted to said grab arms near said jaws and adapted to engage pins on said support to hold said grab arms extended and adapted to be released upon a 80 downward movement of said support relative to said grab arms, thereby allowing the latter to close upon each other, and a discharge valve on said reservoir controlled by said support.

10. Apparatus for raising sunken objects comprising a buoy, a closed reservoir therein adapted to be charged with a pressure medium, a support loosely suspended from said buoy, hooks pivoted to said support and provided with jaws, grab arms held by said jaws, hooks pivoted to said grab arms near said jaws and adapted to engage pins on said support to hold said grab arms extended and adapted to be released upon a 90 downward movement of said support relative to said grab arms, thereby allowing the latter to close upon each other, a discharge valve on said reservoir controlled by said support, and chains attached to said grab arms for limiting their downward movement. 95

11. Apparatus for raising sunken objects comprising a main buoy, a closed reservoir therein adapted to be charged with a pressure medium, a support loosely suspended from said main buoy, hooks pivoted to said support, grab arms supported from said hooks, means for normally holding said grab arms in an extended position and 105 adapted to release said arms upon a downward movement of said support relative to said arms, a discharge valve on said reservoir controlled by said support, links pivoted to said main buoy, auxiliary buoys 115 carried by said links and normally assuming a lowered position, a normally closed means of communication between said auxiliary buoys and said main buoy, and means for opening said means of communication 120 to allow the said auxiliary buoys to become charged with the pressure medium.

12. Apparatus for raising sunken objects comprising a main buoy, a closed reservoir therein adapted to be charged with a pressure medium, a support loosely suspended from said main buoy, hooks pivoted to said support and provided with jaws, grab arms held in said jaws, means for normally holding said grab arms in an extended position 125 130

and adapted to release said arms upon a downward movement of said support relative to said arms, a discharge valve on said reservoir controlled by said support, links 5 pivoted to said main buoy, auxiliary buoys carried by said links, normally held in a lowered position, pipes connecting said auxiliary buoys and said main buoy, cocks in said pipes, an actuating mechanism normally holding said cocks closed, a cable for operating said actuating mechanism to open said cocks, and traction means between said auxiliary buoys and said hooks to separate said hooks and thereby said grab arms upon 10 the ascent of said auxiliary buoys.

13. Apparatus for raising sunken objects comprising a buoy, a closed reservoir therein adapted to be charged with a pressure medium, a grab gear loosely mounted from said buoy, a discharge valve on said reservoir 20 controlled by said grab gear, and vertical fins on the circumference of said buoy to prevent it from turning in the water.

In testimony whereof I have signed my name to this specification in the presence of 25 two subscribing witnesses.
